UNITED STATES PATENT OFFICE.

WILLIAM H. RANKIN, OF WALTHAM, MASSACHUSETTS.

LOOM.

1,134,063.

Specification of Letters Patent. Patented Mar. 30, 1915.

Application filed July 30, 1913. Serial No. 782,020.

To all whom it may concern:

Be it known that I, WILLIAM H. RANKIN, a citizen of the United States, residing at Waltham, in the county of Middlesex and State of Massachusetts, have invented certain new and useful Improvements in Looms; and I do hereby declare the following to be a full, clear, and exact description of the invention, such as will enable others skilled in the art to which it appertains, to make and use the same.

The present invention relates to looms and more particularly to weft replenishing looms.

15 The object of the invention is to improve the construction of weft replenishing looms and particularly the construction of the filling detector mechanism and the magazine for holding filling carriers.

20 With the above object in view the present invention consists in the weft replenishing loom hereinafter described and particularly pointed out in the claims.

In the drawings which illustrate the preferred embodiment of the present invention; Figure 1 is a side elevation of the loom taken partly in section through the magazine and lay on the line 1—1 of Fig. 6; Fig. 2 is a detail view showing the cam for operating the filling detector mechanism; Fig. 3 is a section taken along the line 3—3 of Fig. 2; Fig. 4 is a detail view in the same plane as Fig. 1, showing the feeler entering the active shuttle; Fig. 5 is a detail view 30 similar to Fig. 4, showing the position of the parts after the hammer has transferred a bobbin from the magazine to the active shuttle; Fig. 6 is a plan view of a part of the loom, showing the magazine and filling detector mechanism; Fig. 7 is a detail of the dagger positioning mechanism; Fig. 8 is a section taken partially along the line 8—8 of Fig. 6; Fig. 9 is a section taken partially along the line 9—9 of Fig. 6; and Fig. 10 is a fragmentary plan view illustrating the operation of the filling detector mechanism when the filling in the shuttle is exhausted.

In the illustrated embodiment of the invention the lay 10 is mounted upon lay 50 swords 11 pivoted to the loom frame at 12. The lay is actuated through the connecting rod 13 from the crank shaft 14 which ro-

tates in the direction indicated by the arrow in Fig. 1. On the right-hand end of the lay is the fixed shuttle box 15 and on the left-hand side of the lay are four shifting shuttle boxes 16 which are adapted to hold shuttles containing filling of four different colors or characters. The shifting shuttle boxes are reciprocated up and down to present the shuttle holding the proper colored filling to the picker, by means of a rod 17 slidingly mounted on the lay and connected through a link 18 with an arm 19. The arm 19 is operated by the pattern mechanism (not shown). The above described parts are old and well-known and their construction and operation is understood by those skilled in this art.

Mounted on the right-hand end of frame 30 is a horizontally reciprocating magazine indicated generally by reference numeral 31. This magazine has four compartments for holding single bobbins or filling carriers containing the same colors or characters of filling as the bobbins in the four shuttles. The magazine 31 is reciprocated back and forth in unison with the shifting shuttle boxes 16 so that a bobbin containing filling of the same color as that contained by the active shuttle is always positioned over the fixed shuttle box 15 when the lay is in its forward position. The magazine 31 is reciprocated by means of a rock shaft 32 which extends across the front of the loom 35 and bears on its right hand end an arm 33 in the slotted end of which is loosely received a stud 34 on the magazine 31. The rock shaft is rocked by means of an arm 35 on its left hand end which is connected through a link 36 to the pattern changing arm 19. A pin and slot adjustment 37 is provided for adjusting the amount of movement imparted to the magazine 31.

The magazine 31 consists of a base plate 40 which is dovetailed to slide on the top of the end frame 30 of the loom. Projecting from the side of the base plate 40 are five arms 41, 42, 43, 44 and 45. These arms divide the magazine into four compartments 100 in which are held the filled bobbins 46, 47, 48 and 49. The butts of the bobbins are held by spring pressed plungers 50, mounted on the side of the base plate 40 and engaging

recesses in the bobbin heads. The tips of the bobbins are held in grooved blocks 51 which are slidably mounted on the ends of the arms 41, 42, 43 and 44 and pressed 5 against the bobbin tips by means of springs 56. The filled bobbins are placed in the magazine 31 by hand, the operator placing the recessed butt of the bobbin over the plunger 50 and sliding the tip of the bobbin 10 along the groove 52 in the block 51 until the tip engages the recess 53 in the groove. A yoke piece 54 extends along the end of the magazine, and has buttons 55 around which the loose ends of the filling are wound. The 15 magazine 31 is positioned directly over the fixed shuttle box 15 when the lay is in its forward position at the completion of its beating-up stroke, so that the filled bobbins can be transferred directly from the magazine 31 to the shuttle 20 in the fixed shuttle box 15 by means of a hammer 60. The hammer 60 is pivoted in a bracket 61 on the corner of the loom frame and extends backwardly over the magazine 31. The head of 20 the hammer has a concave face 62 for engaging the bobbin near the butt of the bobbin, and a lateral extension 63 having a concave face at its end for engaging the bobbin near its tip, as is common in hammers of 25 this type.

In order to properly guide the bobbin from the magazine to the shuttle, two yielding latches 64 and 65 are provided. The latch 64 is mounted on the end frame 30 of 30 the loom, and is normally held in raised position by means of a helical spring 66. The latch 65 is mounted on an arm 67 which in turn is mounted upon the end of the hammer bracket 61. The latch 65 is normally 35 held raised by means of a helical spring 68. When the bobbin is driven down by the hammer, the latch 64 engages the bobbin near its butt and the latch 65 engages the bobbin near its tip. The springs 66 and 68 40 allow the latches 64 and 65 to yield and hold the bobbin in proper alinement while it is being transferred from the magazine to the shuttle.

The hammer is actuated by means of a 45 latch 70 which is arranged to be struck by a bunter 71 on the lay. The latch 70 is pivotally mounted at 72 upon the downwardly extending arm 73 of the hammer. The latch is provided with an adjusting screw 74 whereby the movement imparted through 50 the latch to the hammer by the bunter may be varied. A guard 75 mounted on the end frame 30 of the loom extends over the top of the latch and prevents it from being 55 forced up when it is struck by the bunter. The latch normally occupies the position shown in Fig. 1, below the path of movement of the bunter. When a filled bobbin is to be transferred from the magazine to the 60 shuttle, the latch 70 is raised into the path

of the bunter 71 by means of a link 76 which is connected at 77 with the bottom of the latch and drawn rearwardly by means of the filling detector mechanism.

The filling detector mechanism is mounted 70 on the end frame 30 of the loom and comprises a feeler for entering and feeling the filling in the active shuttle and mechanism controlled by the feeler for setting the latch in position to be struck by the bunter. The 75 feeler 80 is formed integrally upon the forward end of a sliding block 81 and is arranged to pass through a hole in the rear wall of the shuttle box 15 and to enter the shuttle 20 through a hole 82 in its rear wall 80 and to feel for the filling on the bobbin in the shuttle. The block 81 is arranged to slide in a box 83 carried upon an arm extending from the end frame 30 of the loom. The middle of the block 81 has a longitudinal slot 84 and the rear of the block 81 is formed with a guiding tail 85. On the side of the feeler block 81 is a laterally projecting pin 86 which is engaged in a slot in the upper end of a feeler actuating bell crank 87. The bell crank 87 is oscillated to reciprocate the feeler by means of a rod 90 which carries an adjustable collar 91 having a pin for engaging a slot in the lower arm of the bell crank 87. The rod 90 is mounted to 95 slide in bearings 92 and 93 secured to the loom frame. The rod 90 is drawn upward by means of a coiled compression spring 94 acting between the top rod bearing 93 and a collar 95 clamped on the rod 90. The lower 100 end of the rod bears a cam roll 96 which is engaged by a cam 97 which operates to draw the rod 90 downwardly. The cam 97 is formed in the right-hand face of a cam wheel 98 which is mounted on the cam shaft 105 99. The cam shaft 99 is geared to the lay crank shaft 14 so as to be driven at one-half the speed of the crank shaft. When the rod 90 is drawn down by the cam 97 the feeler is retracted, and when the cam allows the rod 110 90 to be drawn up by the spring 94, the feeler is advanced.

Pivoted upon a pin 110, which extends across the slot 84 in the feeler block, 115 is a hook 111. The hook 111 has a downwardly projecting beak 112 which, when the hook is pressed down, is adapted to engage a stop lever 113. The hook is normally held raised, however, by means of a spring-pressed plunger 114 mounted in the box 83 and engaging the under side of the shank of the hook. The hook is arranged to be moved downwardly by means of an adjustable stop screw 115 which is adapted to strike against the rear face of the shuttle 20 which is boxed in the stationary box 15 when the filling is exhausted or so nearly exhausted as to allow the feeler 80 to contact or nearly contact with the stem of the bobbin. Normally, 120 when the bobbin is filled or partially filled, 125

the forward movement of the feeler 80 is arrested by the thread on the bobbin so that the head of the stop screw 115 does not come into contact with the rear face of the shuttle. 5 When, however, the head of the stop screw 115 does contact with the rear face of the shuttle, it turns the hook about its pivot pin 110 and brings the beak 112 down against the top of the box 83 in position to engage 10 the lever 113 and draw it forward. The rear faces of the shuttles are provided with wear plates 116 for the engagement of the head of the stop screw 115.

The stop lever 113 is a straight bar pivoted to turn about a substantially vertical pin 120 on the bracket which holds the feeler box 83. The stop lever 113 is prevented from moving up and down both by its mounting on the pin 120 and by the rail 121 on the top of the box 83 beneath which the right-hand end of the lever 113 is slidingly engaged. The lever 113 is normally held in the position indicated in Fig. 10 by means of an extension spring 122 which 25 holds the left-hand end of the lever against a stop 123. When the lever 113 is engaged by the beak 112 of the feeler hook 111 its left-hand end is caught and carried forward with the feeler block, turning the lever 113 30 against the tension of the spring 122. When the lever 113 is thus turned, its left-hand end is brought into the path of movement of the horizontally forwardly extending arm 130 of a latch positioning bell crank 131. 35 The lower end of the bell crank 131 is pivoted at 132 to the link 76 which connects it with the latch so that a downward movement of the arm 130 causes the latch to be raised into the path of the bunter. The bell crank 131 is pivoted at 133 to a collar 134 which is clamped on a vertically reciprocated rod 135. The rod 135 is parallel with the rod 90, and like the rod 90, is slidingly mounted in top and bottom bearings. The 40 rod 135 is drawn upwardly by means of a helical compression spring 136 coiled around the rod between its upper bearing and a collar 137 clamped on the upper end of the rod. The arm 135 is drawn downwardly 45 against the force of the spring 136 by means of a cam roller 139 carried on the lower end of the rod 135, and engaging a cam 138 which is formed on the left-hand face of the cam wheel 98. When the stop lever 113 is 50 in its normal position, the rod 135 as it is reciprocated by the cam 138 and spring 136 carries the bell crank 131 freely up and down. However, when the stop lever 113 is turned by the feeler hook 111 its left-hand 55 end is moved into the path of the arm 130 of the bell crank 131 and stops the arm 130 on the next upward movement of the rod 135. The rod 135 is drawn upward by the spring 136, and the bell crank 131 is turned 60 about its axis 133 (as indicated in dotted

lines in Fig. 7), drawing the link 76 backward and raising the latch 70 into the path of the bunter 71.

The operation of the weft replenishing mechanism is as follows:—Beginning with 70 the loom in the position shown in Fig. 1, the lay crank is on its back center, the shed is open, and the active shuttle is traveling through the shed and is about to be boxed in the stationary shuttle box 15. As the lay 75 begins to move forward on its beating-up stroke the shuttle is boxed in the fixed shuttle box 15. After the shuttle is thus boxed the filling detector mechanism is set into operation to feel for the filling on the bobbin 80 in the active shuttle. The continued rotation of the cam shaft 99 brings the abrupt rise 150 of the cam 97 over the cam roll 96, whereupon the rod 90 is released and is drawn upwardly by its spring 94, causing 85 the feeler 80 to follow and overtake the forwardly moving lay. The feeler 80, acting under the influence of the spring 94 enters the active shuttle and feels for the filling on the bobbin. If there is sufficient filling on 90 the bobbin the feeler 80 is arrested by the filling and the stop screw 115 does not come into contact with the shuttle. The feeler hook 111 is, therefore, allowed to remain in its normal position and the hammer 60 is 95 not operated. Suppose, however, that the filling on the bobbin in the active shuttle is substantially exhausted so that a filled bobbin should be substituted therefor. In that case the feeler 80 is not arrested by the filling, but is allowed to enter the shuttle far enough to bring the head of the stop screw 115 against the shuttle. The forward pressure of the feeler block 81 turns the feeler hook 111 against its spring plunger 114 and 100 brings the beak 112 behind the lever 113. The lever 113 is engaged by the feeler hook before the cam roll 96 reaches the top of the cam rise 150 so that the continued forward movement of the feeler block 81 under the 110 force of the spring 94 causes it to continue to follow the lay forward and carry with it the right-hand end of the stop lever 113, the left-hand end of which is brought over the end of the arm 130. The continued rotation 115 of the cam shaft 99 brings the abrupt rise 151 in the cam 138 over the cam roll 139, allowing the rod 135 to be drawn up by its spring 136 carrying with it the latch positioning bell crank 131. The arm 130 of this 120 bell crank is held by the stop lever 113 and the continued upward movement of the rod 135 under influence of its spring causes the bell crank 131 to be turned about its pivot pin 133 and draw the link 76 rearwardly. The 125 parts have now assumed the position illustrated in Fig. 4, the latch 70 being raised into the path of the bunter 71. Both of the cam rollers 96 and 139 now remain in dwells 130 in the cams and as the lay continues to move

forwardly to beat in the filling, it moves away from the now stationary feeler and the latch 70 is held stationary in the path of the bunter. The lay continues to move forward 5 away from the now stationary feeler, and the feeler 80 is held stationary in its advanced position and the latch is held stationary in its raised position. At the completion of the beating-up stroke of the lay 10 the bunter 71 strikes the latch 70, turning the hammer into the position shown in Fig. 5. The position of the cam wheel 98 at this time is shown in Fig. 2. The hammer 60 when it is driven down transfers a full bobbin from the magazine into the active shuttle, the empty bobbin falling down through 15 the lay. The lay now begins its backward movement and the rods 90 and 137 are drawn down by the cams 97 and 138 so that 20 before the lay crank again comes to its back center the feeler is retracted and the latch has resumed its normal position. As the lay crank passes through its back center the shed is again opened and the active shuttle 25 is driven from the fixed box 15 across the lay into one of the shifting boxes 16 after which the lay again moves forward to beat in the filling. As shown in Figs. 1 and 2, the cam shaft 99 rotates at half the speed of 30 the crank shaft 14 and the cams 97 and 138 are so shaped that the filling detector mechanism remains stationary when the shuttle is 35 boxed in one of the shifting boxes 16.

It is to be noted that the full bobbin is 40 transferred by the hammer into the active shuttle on the same pick in which the filling detector mechanism operates to indicate the exhaustion of the filling, so that, after the filling detector mechanism indicates the exhaustion of the filling, the shuttle does not 45 move out of its box until it is replenished with more filling. This is important as it minimizes the danger of the filling becoming exhausted while the shuttle is traveling through the shed. The mechanism whereby 50 this result is obtained is believed to be highly novel. It is also to be noticed that the access to the open top of the magazine 55 is free and unobstructed so that the operator can easily replace the bobbins which are transferred from the magazine to the shuttle.

While the preferred embodiment of the present invention has been specifically illustrated and described it is to be understood that the present invention is not limited to its preferred embodiment but may be embodied in other constructions of weft replenishing looms within the scope of the invention as defined in the following claims.

I claim—

1. A weft replenishing loom having, in combination, a lay, a magazine for holding filling carriers, filling detector mechanism

supported on the loom frame, independent 65 of the lay, and means set into operation by the filling detector mechanism when the filling in the shuttle is substantially exhausted for transferring a filling carrier from the magazine to the shuttle during the same 70 pick.

2. A weft replenishing loom having, in combination, a lay, a magazine for holding filling carriers, filling detector mechanism supported on the loom frame independent 75 of the lay for operating to feel for the filling in the shuttle during the beating-up stroke of the lay, and mechanism set into operation by the filling detector mechanism when the filling in the shuttle is substantially exhausted 80 for transferring a filling carrier from the magazine to the shuttle at the completion of the same beating-up stroke of the lay.

3. A weft replenishing loom having, in combination, a lay and its crank, a magazine for holding filling carriers, filling detector mechanism supported on the loom frame independent of the lay operating to feel for the filling in the shuttle when the lay is back 90 of its forward or beating-in position, and means set into operation by the filling detector mechanism for transferring a filling carrier from the magazine to the shuttle before the lay crank has turned through a 95 complete revolution.

4. A weft replenishing loom having, in combination, a lay, a magazine for holding filling carriers, filling detector mechanism supported on the loom frame independent of 100 the lay operating to feel for the filling in the shuttle while the shuttle is boxed at the magazine end of the lay, and mechanism set into operation by the filling detector mechanism for transferring a filling carrier from the magazine to the shuttle before the shuttle leaves its box at the magazine end of the lay.

5. A weft replenishing loom having, in combination, a lay, a magazine for holding filling carriers, filling detector mechanism 110 including a feeler mounted on the loom frame which enters the active shuttle from the rear and feels for the filling in the shuttle, and mechanism set into operation by the filling detector mechanism for transferring a filling carrier from the magazine to 115 the shuttle.

6. A weft replenishing loom having, in combination, a lay, a magazine for holding filling carriers, filling detector mechanism 120 including a feeler and means for causing it to follow and overtake the lay and feel for the filling in the shuttle on the beating-up stroke of the lay, and means set into operation by the filling detector mechanism for 125 transferring a filling carrier from the magazine to the shuttle.

7. A loom having, in combination, a lay,

and filling detector mechanism including a feeler and means for causing it to follow and overtake the lay and feel for the filling in the shuttle on the beating up stroke of the 5 lay and weft replenishing means set in operation by the detector mechanism.

8. A loom having, in combination, a lay, and filling detector mechanism including a feeler mounted on the loom frame which enters the shuttle box from the rear and feels for the filling in the shuttle and weft replenishing means set in operation by the detector mechanism.

9. A loom having, in combination, a lay, 15 and a filling detector mechanism including a feeler mounted on the loom frame and mechanism for moving the feeler relatively to the lay to cause the feeler to follow and overtake the lay and enter the shuttle in the 20 lay and feel for the filling in the shuttle while the lay is moving.

10. A loom having, in combination, a lay, and a filling detector mechanism including a feeler mounted on the loom frame and 25 mechanism for actuating the feeler to cause it to enter the shuttle in the lay and feel for the filling in the shuttle during the first part of the beating-up stroke of the lay.

11. A weft replenishing loom having, in 30 combination, a lay, a lay crank and crank shaft, a magazine for holding filling carriers, detector mechanism independent of the lay including a feeler, a cam and cam shaft driven at half the speed of the lay 35 crank shaft and connections between the cam and feeler for causing the feeler to follow the lay, and means set into operation by the filling detector mechanism for transferring a filling carrier from the magazine 40 to the shuttle.

12. A weft replenishing loom having, in combination, a lay, a bunter on the lay, a magazine for holding filling carriers, a hammer for transferring a filling carrier from 45 the magazine to the shuttle in the lay, a latch connected to the hammer, and mechanism for positioning the latch in the path of the bunter including a normally freely movable lever, a feeler arranged to move in 50 the same direction as and relatively to the lay and enter the shuttle and feel for the filling in the shuttle, and mechanism set into operation by the continued movement of the feeler in the same direction as the 55 movement of the lay when the feeler feels a shuttle substantially exhausted of filling for obstructing the movement of the normally freely movable lever to cause it to position the bunter in the path of the lay.

13. A weft replenishing loom having, in combination, a lay, a magazine for holding filling carriers, filling detector mechanism including a feeler block terminating in a feeler, a feeler hook pivoted to the feeler

block, mechanism for moving the feeler 65 block to cause the feeler to follow the lay and enter the shuttle and feel for the filling in the shuttle, an abutment on the feeler hook arranged to contact with the shuttle box when the filling is substantially exhausted and to move the feeler hook relatively to the feeler and a member arranged to be engaged and moved by the feeler hook when the feeler hook is moved by the abutment, and mechanism set into operation 70 upon the movement of said member for transferring a filling carrier from the magazine to a shuttle in the lay.

14. A weft replenishing loom having, in combination, a lay, shifting shuttle boxes on 80 one end of the lay for holding fillings of different color or character, a magazine mounted on the loom frame at the other end of the lay and having a plurality of single bobbin compartments with open tops and bottoms 85 for holding, respectively, each a single bobbin having filling of corresponding color or character, access to the top of the magazine being free and unobstructed to permit the operator to place filled bobbins into the tops 90 of the magazine compartments, a fixed shuttle box on the magazine end of the lay, a hammer mounted on the loom frame, mechanism connecting the shuttle boxes and the magazine for bringing over the shuttle in 95 the fixed shuttle box a bobbin in the magazine of a corresponding color or character, filling detector mechanism adapted to position an element to be struck by the lay at the completion of the same beating-up stroke of 100 the lay during which the feeler has indicated a substantially exhausted bobbin in the shuttle, and mechanism for operating the hammer to transfer a filled bobbin from the magazine to the shuttle in the fixed shuttle box when the filling in the shuttle is substantially exhausted.

15. A weft replenishing loom having, in combination, a lay, shifting shuttle boxes on 110 one end of the lay for holding fillings of different color or character, a magazine mounted on the loom frame at the other end of the lay and having a plurality of single bobbin compartments with open tops and bottoms for holding, respectively, each a 115 single bobbin having filling of corresponding color or character, access to the top of the magazine being free and unobstructed to permit the operator to place filled bobbins into the tops of the magazine compartments, a fixed shuttle box on the magazine end of the lay, a hammer mounted on the loom frame, mechanism connecting the shuttle boxes and the magazine for bringing over the shuttle in the fixed shuttle box a 120 bobbin in the magazine of a corresponding color or character, filling detector mechanism, including a feeler operating to feel

for the filling in the shuttle on the beating-up stroke of the lay, and mechanism for operating the hammer to transfer a filled bobbin from the magazine to the shuttle including a bunter on the lay, a dagger connected with the hammer and a connection between the dagger and filling detector mechanism for positioning the dagger so

as to be struck by the bunter at the completion of the same beating-up stroke of the lay during which the feeler has felt a substantially exhausted bobbin in the shuttle.
